UNITED STATES PATENT OFFICE.

JOHN J. SOMMER, OF NORTH ATTLEBORO, MASSACHUSETTS.

CHAIN JEWELRY.

1,065,006.

Specification of Letters Patent. Patented June 17, 1913.

Application filed March 25, 1913. Serial No. 756,651.

To all whom it may concern:

Be it known that I, JOHN J. SOMMER, a citizen of the United States, and a resident of North Attleboro, county of Bristol, and 5 State of Massachusetts, have invented certain new and useful Improvements in Chain Jewelry, of which the following is a specification.

My invention relates to jewelry known to 10 the trade as "book-link" chains, and consists in the specific construction and arrangement of parts described and claimed, whereby a strong link having the appearance of solidity is formed from sheet metal 15 or "flat stock", and whereby the whole chain is rendered substantial and complete in appearance and finish as hereinafter more fully set forth.

In the accompanying drawings, Figure 20 1, is an elevation of one side of several links of my improved chain, the parts being shown on a scale approximately two-thirds larger than is customary in the trade; Fig. 2, is an edge view of the same; Fig. 3, an 25 elevation of the side of the links opposite to that shown in Fig. 1; Fig. 4, is a view of the outer side of a link blank shown on a scale approximately three-fourths larger than in ordinary practice; Fig. 5, is a view 30 of the inner side of said link blank; Fig. 6, a central longitudinal section of two links, one coupled to the other; Fig. 7, a transverse section of a link, taken upon plane of line 7—7 Fig. 6.

As ordinarily made these chains are 35 comparatively small in size, and are enlarged in the drawings forming part of this specification for convenience of illustration. Each link is made of a blank stamped out of 40 "flat-stock," the shape of the blank being clearly shown in Figs. 4 and 5. At one extremity the blank B, is formed with the female coupling tongue f, having the eyelet hole f', and at the other extremity the blank 45 is formed with the male coupling tongue e, adapted to enter the eyelet f', as shown in Fig. 6. Medially the blank is formed with the transverse openings a, a, on either side of the portion of the blank which constitutes 50 the coupling bar b. The edges of the

blank adjacent to the bar b, and openings a, a, are recessed as at e, e, to facilitate the bending and doubling over of the blank upon itself as shown more particularly in Figs. 6 and 7. The longitudinal edges of 55 the blank are upset to form inturned flanges i, i, the opposed edges of which contact with each other when the blank is bent double as above stated, and as clearly shown in Fig. 7, of the drawings. These side flanges, which 60 may be slightly flared or beveled as related to the flat sides s, s, of the link, or otherwise shaped as may be found expedient, are an important factor in my construction and arrangement of parts since they not only 65 stiffen and reinforce the flat sides s, s, of the link and strengthen the latter as a whole, but they also bridge over and inclose the space between said flat sides s, s, and thereby impart a solidity of appearance to the 70 links and chain which is much more apparent in the actual size of chain than in the accompanying drawings which, obviously and necessarily render intermediate spaces more apparent than they really are in actual 75 size of chain. Fig. 2, gives a fair representation of the result attained in this respect, although the coupling means are much more conspicuous than in reality.

The method of coupling the links together 80 is shown in Fig. 6,—the female tongue f, being passed through the holes a, a, and around the coupling bar b, of the preceding link blank, and into the space between the broad flat sides s, of the link, the coupling 85 tongue e, being then inserted through the eyelet f', and bent over the end of the tongue f, thereby effectually and permanently coupling the parts together in such manner as to admit of necessary articulation between 90 links.

The contacting edges of the inturned side flanges i, i, may be soldered together or otherwise united,—and the usual finish resorted to, concealing the joints, and imparting 95 an appearance of solidity and symmetry of structure that adds materially to the attractiveness and value of the chain, while materially strengthening and reinforcing the same.

What I claim as my invention and desire to secure by Letters Patent is,

A chain of the character designated, comprising a series of links articulately connected, each link consisting of a blank of sheet metal formed with a coupling bar and openings adjacent thereto, with interlocking tongues for coupling with a preceding

link, and with inturned longitudinal edge flanges contacting with each other in the manner and for the purpose set forth.

JOHN J. SOMMER.
